UNITED STATES PATENT OFFICE

JOHN L. LOCKLIN, OF LAWRENCE, NEW YORK

DESIGN FOR A BILL FRAME

Application filed February 8, 1932. Serial No. 42,765. Term of patent 3½ years.

To all whom it may concern:

Be it known that I, JOHN L. LOCKLIN, a citizen of the United States, and a resident of Lawrence, county of Nassau, and State of New York, have invented a new, original, and ornamental Design for a Bill Frame, of which the following is a specification, reference being had to the accompanying drawing, forming a part thereof.

I claim:

The ornamental design for a bill frame as shown.

JOHN L. LOCKLIN.
